2-METHYL-7-TRIFLUOROMETHYL-4H-3,1-BENZOXAZINE-4-ONE

Leo Henryk Sternbach, Upper Montclair, N.J., and Gabriel Saucy, Richen, Switzerland, assignors to Hoffmann-La Roche Inc., Nutley, N.J., a corporation of New Jersey
No Drawing. Filed Mar. 23, 1962, Ser. No. 182,131
Claims priority, application Switzerland Dec. 2, 1960
1 Claim. (Cl. 260—244)

This invention relates to 2-amino-trifluoromethylbenzophenones as well as precursors and derivatives thereof. More particularly, the invention relates to compounds of the structural formula

(I)

wherein R₁ is chosen from the group consisting of hydrogen and lower alkyl, R₄ is chosen from the group consisting of hydrogen, halogen, nitro, amino and trifluoromethyl.

The invention relates also to the compounds which are intermediates for these amino-benzophenones and to the compounds which can be produced from them.

2-amino-trifluoromethylbenzophenones are especially valuable for the synthesis of benzodiazepine compounds, e.g. compounds represented by one of the following formulas

(II)

(III)

wherein A represents a carbon nitrogen grouping which completes the seven-membered diazepine ring and which is selected from the group consisting of

and

2

R₁, R₂, R₃ and R₇ each represent a member of the group consisting of hydrogen and lower alkyl, R₄ is chosen from the group consisting of hydrogen, halogen, nitro, amino and trifluoromethyl.

5 These compounds (i.e. those of Formulas II and III above) are valuable therapeutic agents. In addition to the compounds within the scope of Formulas II and III above there are also encompassed in the invention the pharmaceutically acceptable salts of said compounds. Certain compounds of the above formulas form pharmaceutically acceptable acid addition salts and/or pharmaceutically acceptable quaternary ammonium salts. Thus, the basic benzodiazepine compounds (i.e. those of Formulas II and III above except those illustrated by Formula VI

10 below) of the invention form acid addition salts by reaction with inorganic and organic acids such as mineral acids, e.g. hydrohalic acids, for example by hydrochloric acid, hydrobromic acid and the like, nitric acid, sulfuric acid, phosphoric acid, etc. and acetic acid, methanesul-

15 fonic acid, succinic acid and the like. Also the compounds containing a tertiary amino nitrogen atom in the 4-position, i.e. the compounds of Formulas II and III wherein R₇ is lower alkyl, form pharmaceutically acceptable quaternary salts with conventional quaternizing

20 agents such as lower alkyl halides and the like.

25 The compounds formed during the synthesis of the trifluoromethyl-benzophenone and those formed during the preparation of the benzodiazepines are novel compounds which, except as pointed out below, are within the scope of this invention.

The 2-amino-trifluoromethylbenzophenone compounds of the invention can be produced by a variety of methods, which are illustrated in detail in the examples to follow. One method involves the reaction of an anthranilic acid

30 derivative with acetic anhydride to produce a 2-methyl-3,1-benzoxazin-4-one. By reacting this latter compound with a phenyl Grignard agent and hydrolyzing the resulting crude product, the desired 2-amino-trifluoromethylbenzophenone can be obtained. When an anthranilic acid

35 starting material bearing a trifluoromethyl substituent is used, the ring bearing the 2-amino substituent in the benzophenone is substituted by a trifluoromethyl group. However, if the phenyl Grignard agent is substituted by a trifluoromethyl group, then the benzophenone benzene

40 ring which does not contain the 2-amino group will be trifluoromethyl substituted. Also a 3,1-benzoxazin-4-one, derived from a trifluoromethyl-substituted anthranilic acid, can be reacted with a trifluoromethyl-substituted phenyl

45 Grignard agent to yield a 2-amino-bis(trifluoromethyl)-

50 benzophenone.

The 2-aminotrifluoromethylbenzophenones can be converted with glycine or an ester thereof to form trifluoromethyl-5-phenyl-3H-1,4-benzodiazepin-2(1H)-ones which have the structural formula

55 (IV)

60 70 wherein R₁ and R₄ have the same meaning as above.

If, instead of glycine or its ester, a longer chain α -amino acid or ester thereof is used, for example α -alanine

or its ester, then a substituent can be introduced into the 3-position, e.g.

(V)

wherein R₁, R₂ and R₄ have the same meaning as above.

Alternatively, 2-amino-trifluoromethylbenzophenones can be treated with hydroxylamine hydrochloride to form corresponding 2-amino-trifluoromethylbenzophenone oximes. Reaction of the oxime with chloroacetyl chloride in acetic acid produces the chloroacetamino derivative which cyclizes to form a 2-chloromethyl-4-phenylquinazoline 3-oxide bearing a trifluoromethyl substituent. The last named compound can then be reacted with an alkali metal hydroxide or alkaline earth metal hydroxide, preferably in an inert organic solvent such as alcohol, acetone, dioxane, and the like, to enlarge the ring and produce a 5-phenyl-3H-1,4-benzodiazepin-2(1H)-one 4-oxide bearing a trifluoromethyl substituent and having the structural formula

(VI)

wherein R₁ and R₄ have the same meaning as above, or it can be reacted with ammonia or lower alkylamine to yield a 2-amino-5-phenyl-3H-1,4-benzodiazepine 4-oxide or a 2-lower alkylamino-5-phenyl-3H-1,4-benzodiazepine 4-oxide, respectively. The latter two products can be represented by the structural formula

(VII)

wherein R₃ and R₄ have the same meaning as above.

The compounds of Formula VI can be converted to compounds of Formula IV by treatment with phosphorus trichloride or by catalytic hydrogenation, for example in the presence of Raney nickel. By the same procedures, compounds of Formula VII can be converted into compounds represented by the formula

(VIII)

wherein R₃ and R₄ have the same meaning as above.

10

When 5-phenyl-3H-1,4-benzodiazepine compounds, i.e. compounds of Formulas IV, V and VIII above, are reduced with hydrogen in the presence of a platinum catalyst, the corresponding 5-phenyl-4,5-dihydro-3H-1,4-benzodiazepines are obtained, i.e. those compounds of Formulas II and III wherein A represents

are produced.

The compounds corresponding to Formula II (i.e. Formulas IV, V and VI) wherein R₁ is hydrogen and those corresponding to Formulas II and III, wherein R₇ is hydrogen can be modified so that R₁ and/or R₇ are lower alkyl by a variety of methods. Compounds of Formula II wherein R₁ is lower alkyl can be obtained by reacting corresponding compounds wherein R₁ is hydrogen with a diazo-alkane, alkyl sulfate or alkyl halide, in a medium such as ether, benzene, alcohol or dioxane. Further, the compounds of formula II wherein R₁ is lower alkyl can be obtained directly from 2-(N-lower alkyl)-aminobenzophenones. Compounds of Formula II wherein R₁ is lower alkyl and R₇ is hydrogen can be converted into corresponding compounds wherein R₇ is lower alkyl by reaction with a lower alkyl halide. By alkylation of compounds of Formula II wherein R₁ and R₇ are both hydrogen and by altering the conditions of the reaction, any one of four reaction products can be obtained. More explicitly, the four reaction products which can be obtained are those wherein the 1-position hydrogen alone is replaced, those where the 4-position hydrogen alone is replaced, those where both the 1- and 4-position hydrogens are simultaneously replaced and those where the 4-position nitrogen is quaternized. Thus, treatment of a solution of a compound of Formula II, wherein A is

and both R₁ and R₇ are hydrogen, with an excess of lower alkyl halide gives the corresponding derivative wherein R₇ is converted to lower alkyl, while prolonged heating results in the quaternization of the 4-position nitrogen atom. On the other hand, by using sodium methoxide, sodium hydride or the like, to form the sodio derivative of the 1-position nitrogen atom, and reacting this with an equivalent amount of lower alkyl halide, the corresponding compound of formula II wherein only the 1-position nitrogen atom is substituted is obtained. Using an excess of lower alkyl halide and prolonged heating with a sodio derivative of a compound of Formula II wherein either both R₁ and R₇ are hydrogen, or wherein R₁ alone is hydrogen, results in the 1,4-di-lower alkyl compound wherein both R₁ and R₇ are lower alkyl. Further, as discussed above, this 1,4-disubstituted compound can also be obtained by heating a compound wherein R₁ is lower alkyl and R₇ is hydrogen with an excess of lower alkyl halide.

The direct synthesis of the benzodiazepinones by reaction of the 2-amino-trifluoromethylbenzophenones with an α -amino acid or ester thereof forms an important feature of the invention. According to this method the ketone is heated with an α -amino acid or ester thereof such as glycine or a glycine ester; for example a glycine lower alkyl ester such as glycine ethyl ester, α -alanine or an α -alanine lower alkyl ester, and the like. The reaction is preferably effected in a solvent such as pyridine, dimethylformamide, and the like. It is also preferable

75

to have an ion of a strong acid present in the reaction mixture and therefore it is convenient to use reagents in the form of the salt of a strong organic or inorganic acid, e.g. glycine hydrochloride, glycine ethyl ester hydrochloride, α -alanine hydrochloride, α -alanine methyl ester hydrochloride or part of the pyridine as pyridine hydrochloride.

Benzodiazepin-one compounds corresponding to Formula IV above can also be produced by reacting a 2-aminotri fluoromethylbenzophenone corresponding to Formula I above, with an α -halo-lower alkanoyl-halide, such as chloracetyl chloride, bromoacetyl bromide, α -bromo-propionyl bromide and the like, to produce a 2-(α -halo-lower alkanoylamino)-trifluoromethylbenzophenone corresponding to the formula

(IX)

wherein R₁ and R₄ have the same meaning as above, and R₆ is selected from the group consisting of hydrogen and lower alkyl.

The compounds corresponding to Formula IX can then be directly cyclized by reaction with ammonia to yield compounds corresponding to Formula IV above or they can be reacted with ammonia so that the halogen atom is replaced by the amino group yielding a 2-(α -amino-lower alkanoylamino)-trifluoromethylbenzophenone which then can be cyclized to a compound corresponding to Formula IV above. The 2-(α -amino-lower alkanoyl-amino)-trifluoromethylbenzophenones and the method of cyclizing them to compounds of Formula IV above are not a part of this invention but are disclosed herein in order that the present disclosure may be complete.

Any of the compounds of Formulas I-IX above can be treated with an agent which introduces a nitro group into a position on one of the benzene rings thereof. Further, any nitro group present in any of the compounds of Formulas I-IX above can be reduced to an amino group.

The benzodiazepin compounds corresponding to Formulas II and III above, which are inclusive of the compounds corresponding to Formulas IV through VIII above, are valuable as therapeutic agents. They are useful as sedatives and anti-convulsants and can be used as tranquilizers and muscle relaxants. These compounds can be administered parenterally or orally in therapeutic dosage in solid or liquid dosage forms such as tablets, capsules, suspensions, elixirs and the like. The compounds which are basic in character can be administered in the form of the medicinally acceptable acid addition salts and those with a tertiary nitrogen atom in the 4-position can be administered in the form of their quaternary ammonium salt.

The following examples are illustrative of the invention but not limitative thereof. All temperatures are in degrees centigrade.

Example 1

75.9 g. of sodium nitrite were added slowly with stirring to 445 ml. of concentrated sulfuric acid at 0-10° C. After the addition was completed, the reaction mixture was allowed to stir without external cooling, whereupon the temperature rose to about 70° C. and the solution turned turbid. After cooling to 30° C., 206 g. of 2-nitro-4-trifluoromethyl-aniline were added in portions over a period of about 2 hours, the temperature being kept at 30 to 35° C. Stirring was continued for an additional 1½ hours at room temperature. Then, the reaction mix-

ture was poured over 1.35 kg. of ice. A small amount of insoluble material was filtered off and the filtrate treated with 270 g. of zinc-chloride, dissolved in a small amount of water. After cooling for several hours to 0° C., the precipitated diazonium zinc chloride double salt was filtered off and washed with a small amount of saturated sodium chloride solution. To a cold solution of 147 g. of sodium cyanide and 89.5 g. of cuprous cyanide in 750 ml. of water, the wet diazonium compound described above was added in small portions. During the addition, the temperature was kept below 20° C. After addition of 30 g. of sodium bicarbonate, the reaction mixture was stirred at room temperature for 2 hours. Then, it was heated for half an hour on a steam bath to 70° C. After cooling, water and ether was added to the reaction mixture; then, it was acidified, filtered and the filtrate extracted with ether the usual way to give an oil, which was purified by distillation. The fractions between 85-110°/1-2 mm. Hg solidified and contain the 2-nitro-4-trifluoromethylbenzonitrile.

Example 2

100 g. of 2-nitro-4-trifluoromethylbenzonitrile were dissolved in 2.5 liters of methanol and hydrogenated at atmospheric pressure in the presence of 20 g. of wet Raney nickel catalyst. The reaction was continued until 3 molar proportions of hydrogen were absorbed. The catalyst was filtered off and the methanol solution was evaporated to dryness. The residue was crystallized from a mixture of ether and petroleum ether. The 4-trifluoromethyl-anthranilic acid amide formed colorless needles melting at 151-152°.

Example 3

68.5 g. of 4-trifluoromethylanthranilic acid amide were refluxed with 700 ml. of a 50% sulfuric acid solution for one hour, then poured onto ice. The precipitated reaction product was filtered off and washed with water. The 4-trifluoromethylanthranilic acid was crystallized from a mixture of ethanol and water and then melted at 175°.

Example 4

A solution of 23 g. of 4-trifluoromethylanthranilic acid in 150 ml. of acetic anhydride was refluxed for one hour. Then the solvent was removed by distillation under reduced pressure and the residue was crystallized from benzene-hexane to obtain 2-methyl-7-trifluoromethyl-4H-3,1-benzoxazin-4-one, M.P. 68-70°.

Example 5

50 A solution of phenylmagnesium bromide, prepared from 2.4 g. of magnesium, 15.2 g. of bromobenzene and 150 ml. of ether, was added to a solution of 18 g. of 2-methyl-6-trifluoromethyl-4H-3,1-benzoxazin-4-one in 100 ml. of benzene while stirring and cooling with ice. The Grignard reagent was added slowly over a period of one hour. After stirring for one additional hour at 5°, the reaction mixture was treated with ice and ammonium chloride. The crude reaction product was extracted with ether. The extract was concentrated in vacuo and the residue was refluxed for one hour with a mixture of 100 ml. of 3 N sodium hydroxide and 100 ml. of methanol. The reaction mixture was extracted with benzene. The benzene extract was concentrated in vacuo and the residual, crude 2-amino-4-trifluoromethylbenzophenone was dissolved in hexane and purified by chromatography using a 20 fold amount of neutral alumina (Brockmann activity state III). Elution with a mixture of hexane-ether (1:1) and evaporation yielded yellow 2-amino-4-trifluoromethylbenzophenone which was recrystallized from hexane, M.P. 55-56° (corr.).

Example 6

2 g. of 2-amino-4-trifluoromethylbenzophenone were reacted with 2.0 g. of glycine ethyl ester hydrochloride in pyridine precisely as described in Example 5. The crude reaction product was crystallized from ether-hexane to

yield pure 8-trifluoromethyl-5-phenyl-3H-1,4-benzodiazepin-2(1H)-one, M.P. 186-186.5°.

By following the procedure described in Examples 6, 7, 8, 12 and 13 but using 2-amino-4-trifluoromethylbenzophenone as the original starting material, 8-trifluoromethyl - 5 - phenyl-3H-1,4-benzodiazepin-2(1H)-one 4-oxide, 8 - trifluoromethyl-2-amino-5-phenyl-3H-1,4-benzodiazepine 4-oxide and 8-trifluoromethyl-2-methylamino-5-phenyl-3H-1,4-benzodiazepine 4-oxide are obtained.

The present application is a continuation-in-part of application Serial No. 103,727, filed April 18, 1961 and now pending and application Serial No. 2,605, filed January 15, 1960, and now pending.

We claim:

2-methyl-7-trifluoromethyl-4H-3,1-benzoxazin-4-one.
